BOTTLE CARRIER

Stephen Lighter, Milwaukee, Wis.

Application October 29, 1951, Serial No. 253,630

6 Claims. (Cl. 220—113)

1

This invention relates generally to bottle carriers and more particularly to a paperboard container for the transportation of bottled goods such as soft drinks and the like.

It is the practice in the retail sale of soft drinks, beer, and other beverages to provide the vendee with a container for carrying his purchases to his home. The margin of profit is so small in the case of most bottled beverages that the container provided must be of very inexpensive construction, particularly since psychological factors prohibit the use of anything but a non-returnable container. The fact that the cost must be low militates against the use of any material but paperboard. Even then, the quality of the paperboard and the quantity thereof is determined by the value of the bottled article, expensive bottled goods such as medicines, for instance, permitting the use of larger amounts of paperboard of high quality because of the higher profit margin. In view of the above-described situation, many paperboard bottle carriers have been developed, with varying degrees of success. Because of the low allowable cost of the bottle carrier, certain compromises must be made with the most desirable quantity and quality of paperboard used in the construction. Because of these limitations, considerable ingenuity has been used in the past in designing carriers having a satisfactory strength and yet which use very little material. Most of these carriers of the prior art are deficient in one respect or another. For instance, the most popular constructions are made from a single blank and usually have a center panel and an outer wall with dividers extending therebetween; when the dividers are formed from the outer wall, the outer wall is limited in vertical height, which means that carriers of this type cannot be stacked one on top of the other. On the other hand, when the carrier is made with the dividers formed from the center panel, the center panel cannot be connected with the remainder of the container in a manner to give sufficient strength. In all prior art carriers the dividers, whether formed from the center panel or from the outer wall, are of limited vertical extent and thus permit adjacent bottles to touch one another which is an objectionable feature because of the scratching and breaking which results therefrom. Many previously used constructions have only one thickness of paperboard under the bottle or do not otherwise provide for cushioning thereunder and this causes breakage during use, but most particularly during loading when the bottles are dropped into the carrier from a considerable distance by the loading machine.

2

The present device obviates the above-recited difficulties in a manner that will be evident from the description which follows.

It is accordingly an outstanding object of the present invention to provide a paperboard bottle carrier which permits of an outer wall of any desired vertical extent.

Another object of this invention is to provide a paperboard bottle carrier which is of a construction wherein the center panel remains strong even though dividers are formed integral therewith.

A still further object of the instant invention is the provision of a bottle carrier which provides each bottle held therein with walls on four sides and which prevents adjacent bottles from touching.

Still another object of the invention is the provision of a bottle carrier having an unusually strong and resilient multi-ply bottom construction.

Another object of this invention is the provision of a bottle carrier which can be formed from a single blank, which can be constructed on automatic machinery, which folds flat when assembled but can be promptly expanded to operative condition, and which is economical in the quality and quantity of paperboard required in its fabrication.

With these and other objects in view, as will be apparent to those skilled in the art, the invention resides in the combination of parts set forth in the specifications and covered by the claims appended hereto.

The character of the invention, however, may be best understood by reference to certain of its structural forms, as illustrated by the accompanying drawings in which:

Fig. 1 is a view of a blank from which the bottle carrier of the invention may be constructed;

Fig. 2 is a view of the invention in the process of assembly;

Fig. 3 is a view of the device of the invention at a later point in the assembly;

Fig. 4 is a plan view of the completed bottle carrier of the invention;

Fig. 5 is a sectional view of the device of the invention taken on the line 5—5 of Fig. 4;

Fig. 6 is a sectional view of the invention taken on the line 6—6 of Fig. 4;

Fig. 7 is a view of the invention in collapsed condition;

Fig. 8 is a perspective view of the invention at an intermediate point in the process of expanding it to operative condition;

Fig. 9 is a perspective view of the carrier of the

invention in completely expanded condition; and

Fig. 10 is a perspective view of the invention with portions broken away to show the details of construction.

Like reference characters denote similar parts in the several figures of the drawings.

A complete understanding of the present invention may best be conveyed by a description of the blank from which it is formed. Referring, then, to Fig. 1, the blank, generally designated 10, is formed in one piece from paperboard or similar material by any of the methods well known in the art. The blank 10 comprises a lower bottom panel 11 of generally elongated rectangular shape, the width being somewhat greater than twice the diameter of the type of bottle with which the carrier is to be used and the length being somewhat greater than three times the diameter of such a bottle. The blank 10 further comprises an upper bottom panel 12 of the same size and shape as panel 11 and situated end to end therewith and being defined therefrom by a cut 13 extending entirely across the common end of the two panels. Extending longitudinally of the panel 11 is a score line 14 and the panel 12 is provided with a similar score line 15; the two score lines are aligned with one another and constitute an axis of symmetry for the entire blank. Since the halves of the blank which reside on opposite sides of the score lines 14 and 15 are mirror images of one another, only one of these halves will be described, it being assumed that the other half is exactly similar.

The blank further comprises a side panel 16 hingedly attached to the bottom panel 11 and defined therefrom by score line 17. The side panel is of generally square shape and is co-extensive with the panel 11. An end panel 18 is hingedly attached to the side panel 16 and is defined therefrom by a score line 19. The end panel 18 is co-extensive with the side panel 16 along a side adjacent to the score line 17 and is of a width approximately half the width of the bottom panel 11.

The blank further comprises a center panel 20 which is hingedly attached to the end panel 18 on the side edge thereof opposite the panel 16 and is defined from the panel 18 by a score line 21. The center panel 20 is of approximately the same shape as the panel 16 and is co-extensive with the end panel 18; it is further provided with a handle aperture 22 situated adjacent one edge, as shown. The blank further comprises a divider panel 23 which is hingedly attached to panel 16 and to panel 12. The divider panel 23 is defined from panel 16 by a score line 24 and is co-extensive with said panel. The panel 23 is defined from the panel 12 by a score line 25 which score line is interrupted by two cuts 26 and 27 whose purpose will be described more fully hereinafter. The panel is co-extensive with the panel 12 and extends therebeyond a slight amount.

It can be seen, then, that the panels 23, 16, 18 and 20 form an elongated rectangle whose width will ultimately constitute the height of the completed carrier; this dimension will usually be selected as slightly greater than the height of a bottle.

The upper bottom panel 12 is provided along each side with cuts and scores of the following description: three cuts 28, 29 and 30 originate at the score line 25 and extend diagonally across the panel toward the cut 13. Three score lines 31, 32 and 33 originate in the score line 25 and extend diagonally across the panel in a direction

away from the cut 13. Each cut extends to a point where it meets a score line, at which point the score line also terminates, the angle of meeting being about a right angle and the length of all cuts and score lines being equal. The cuts 26 and 27 on the score line 25 start at the intersection of cut 29 and score line 31 and at the intersection of cut 30 and score line 32, respectively, and extend a short distance along the score line 25 in a direction away from the panel 16.

The divider panel 23 is provided with cuts and scores defining dividers for the carrier. A score line 34 extends across the panel 23 from the score line 25 in a line with the end of the panel 12 which is opposite the panel 11. The score line 34 terminates a little more than half way across the panel at which termination it is met by a cut 35 which extends at an acute angle to the score line 25. The cut 35 terminates at its intersection with a cut 36 running parallel to the score line 25. The cut 36 intersects and terminates at a score line 37 which extends parallel to the score line 24 from the cut 36 to the edge of the panel 23 opposite the score line 25. The score line 37 is parallel to the score line 24 and resides at a distance therefrom approximately equal to the width of the end panel 18.

A cut 38 extends across the panel 23 from the end of the cut 27 which is away from the point of intersection of the cut 30 and the score line 32; the cut 38 lies parallel to the score line 24 and terminates in its intersection with an angular cut 39. The cut 39 extends in the direction of the score line 24 until it meets and is terminated at a score line 40. The score line 40 is aligned with the score line 37 and extends from the score line 25 across the panel to a point which is intermediate of the point of its intersection with the cut 39 and the point of intersection of the score line 37 with the cut 36. From the said intermediate point of termination of the score line 40 there extends a cut 41 parallel to score line 25. The cut 41 merges into a short, angular cut 42 which, in turn, meets and terminates at a cut 43. The cut 43 extends from its intersection with the cut 42 parallel to the score line 24 and ends on the score line 25 at the end of the cut 26 which is away from the intersection of the cut 29 and the score line 31. A score line 44 extends from the point of intersection of the cut 29 and the score line 31 parallel to the score line 24, crosses the angular cut 42, and terminates at the point of intersection of the angular cut 35 and the cut 36. A curved cut 45 joins the intersection of the cut 36 and the score line 37 with the intersection of the score line 40 and the angular cut 39. A handle aperture 46 is provided in the panel 23, as shown.

The cuts and score lines in the divider panel 23 define a number of separate portions therewithin. The score line 24, the score line 25, the score line 40, the curved cut 45, and the score line 37 define an end panel 47. The score line 37, the cut 36, the cut 35, and the score line 34 define a center panel 48. The score line 34, the cut 35, the score line 44, the cut 42, the cut 43, and the score line 25 define a divider 49. The cut 36, the curved cut 45, the score line 40, the cut 41, the cut 42, and the score line 44 define an attaching member such as a glue area 50. The score line 25, the score line 44, the cut 42, the cut 41, the score line 40, the cut 39, and the cut 38 define a divider 51. The cut 26, the cut 43, the cut 42, and the score line 44 define a blue tab 52. The cut 27, the cut 38, the cut 39, and the score line 40 define a glue tab 53.

Referring next to Fig. 2, wherein are shown two stages in the assemblage of the blank into the finished carrier, it can be seen that the upper bottom panel 12 and the divider panels 23 have been rotated out of the plane of the drawing about an axis determined by the score lines 24 and the cut 43, the rotation taking place until the above-enumerated panels lie face-to-face with their respective adjacent panels. For instance, panel 12 lies in juxtaposition to the lower bottom panel 11. The glue area 50 is glued or otherwise fastened to the side panel 16. The carrier is then in the condition shown in the lower part of Fig. 2.

Next, the center panel 48 is moved away from contact with the side panel 16; at the same time the end panel 47, the divider 51, and the divider 49 are moved to reside at right angles to the side panel 16. At the same time, the glue tabs 52 and 53 are moved to reside at right angles to their respective dividers; the dimensions selected are such that, when this is done, the glue tabs reside in the plane of the center panel 48. In order that these movements may take place, it is necessary that the divider panel 23 and the side panel 16 be rotated at the same time about the score lines 17 and 25, which lines now lie adjacent and coextensive with one another. The above-described movements bring about another movement and that is the movement of the triangular areas 54 defined by the cuts 28, 29, and 30, the score lines 31, 32, and 33 and the score line 25. These triangular areas 54 rotate about the score lines 31, 32, and 33 through 180 degrees until they lie in face-to-face relation to fixed remaining portion of the panel 12 from which they originated. The upper portion of Fig. 2 shows the condition of the carrier when the above-described movements are partially completed.

After the movements described above are completed, the end panel 48 is rotated about the score line 19 to a position at a right angle to panel 16 and the center panel is rotated about the score line 21 until it resides in face-to-face relationship to the center panel 48 and the glue tabs 52 and 53. The center panel 48 and the glue tabs 52 and 53 are glued or otherwise fastened to the center panel 20 with the handle apertures 22 and 46 in registry.

The carrier now has the appearance shown in Fig. 3 in which the portions of the center panel 20 to which the center panel 48 and the glue tabs 52 and 53 are attached are stippled. It only remains to glue the two center panels 20 together to complete the carrier.

Fig. 4 is a view of the completed bottle carrier of the invention looking downwardly into it. The triangular areas 54 are shown particularly well in this view. It is clearly shown, also, that the arrangement of the parts and their dimensions is such that the carrier is divided into six equally sized compartments of a size to receive the particular bottle for which the carrier was designed.

Fig. 5, which is a vertical, transverse sectional view of the carrier shows particularly well the shape of the dividers.

Fig. 6, which is a vertical, longitudinal sectional view of the carrier, shows certain details of construction. Particularly, it shows that the center panel 48 does not entirely overlay the center panel 20. The manner in which the triangular areas 54 serve to provide a triple thickness of paperboard under each bottle is also made evident.

It is to be understood that the above-recited

manner of assembling the carrier from the blank is not necessarily the manner which would be used in mass production of the item; the above description was given to permit clearer understanding of the construction of the invention. The usual automatic machine will produce the carrier in the flat, folded condition shown more or less schematically in Fig. 7. When the carrier is to be loaded with bottles, pressure is brought to bear on the ends, as indicated by the arrows. As the carrier expands into open position it assumes the aspect shown in Fig. 8, and finally, when completely expanded, appears as in Fig. 9.

The perspective view of Fig. 10 is very helpful in gaining an understanding of the present invention. It is particularly to be noted that the handle apertures in four thicknesses of paperboard provided a broad hard surface that will not cause the person holding the carrier and bottles discomfort. The manner in which the triangular areas 54 provide a resilient pad for each bottle is clearly illustrated; it can be seen, also, that the weight of the bottle on each of these triangular areas serves to retain the carrier in expanded condition. In addition, the triangular areas snap into position and serve to retain the container in expanded condition even when no bottles are present. It should be noted that the dividers are permitted, by the construction of the invention, to extend vertically and transversely an ample amount so as to afford proper protection against the bottles touching one another.

It is to be appreciated that the fact that the structure of the present invention is such as to permit a side panel 16 which is unlimited in vertical extent also means that the top edge of the side panel could be furnished with an integral cover for the carrier or with any similar appendage. Also, the triangular areas 54, which serve to lock the container in expanded condition, among other functions, need not be of that particular shape as long as the locking is carried out in the manner described. The importance of the fact that the present invention permits the center panel to extend completely to the bottom of the carrier and the side panel to be of unlimited vertical extent cannot be overemphasized; in prior art devices one or the other of these features had to be sacrificed to permit the dividers to be punched from the panels.

It is obvious that minor changes may be made in the form and construction of the invention without departing from the material spirit thereof. It is not, however, desired to confine the invention to the exact form herein shown and described, but it is desired to include all such as come within the scope claimed.

The invention having been thus described, what is claimed as new and desired to secure by Letters Patent is:

1. A bottle carrier formed from a single blank of paperboard, comprising: a side panel, a center panel, a divider panel, a bottom panel, said center panel and said divider panel being fastened together in face-to-face relation and normally residing in spaced, parallel relation to the side panel with the divider panel facing the side panel, a first divider extending from the divider panel to the side panel, a glue area hingedly attached to the first divider and fastened to the side panel in face-to-face relation therewith, a second divider hingedly attached to said glue area and extending to the center panel, a glue

tab attached to the second divider and to the center panel, the said dividers extending downwardly between the panels to the bottom edges thereof, a connecting portion joining each of the dividers to the bottom panel, each connecting portion being hingedly attached to the bottom edge of its respective divider and being hingedly attached to the bottom panel along a line which lies at an acute angle to the line of attachment of the connecting portion to the bottom edge of the divider.

2. A bottle carrier formed from a single blank of paperboard, comprising: a side panel, a center panel, a divider panel, a bottom panel, said center panel and said divider panel being fastened in face-to-face relation and normally residing in spaced, parallel relation to the side panel with the divider panel facing the side panel, a first divider formed from the divider panel and extending therefrom to the side panel, a glue area formed from the divider panel hingedly connected to the first divider and fastened in face-to-face relation with the side panel, a second divider formed from the divider panel hingedly connected to the glue area and extending to the center panel, a glue tab attached to the second divider and fastened to the center panel, the said dividers extending downwardly between the panels to the bottom edges thereof, a triangular area formed from the bottom panel and connecting each of the dividers to the bottom panel, each triangular area being hingedly joined along one side to the bottom edge of its respective divider and being hingedly joined along another of its sides to the bottom panel along a line which lies at an acute angle to the line of connection of the triangular area to the divider.

3. A bottle carrier as recited in claim 2, wherein: the side panel extends above the top edges of the said dividers a considerable distance.

4. A bottle carrier formed from a single blank of paperboard, comprising: a lower bottom panel, a side panel hingedly connected to the bottom panel, a first end panel hingedly connected to an edge of the side panel adjacent the connection with the bottom panel, a center panel hingedly connected to an edge of the first end panel opposite to the connection to the side panel, a second end panel hingedly connected to an edge of the side panel opposite the connection with the first end panel, a divider panel hingedly connected to the second end panel along an edge opposite to the connection thereof to the side panel, an upper bottom panel for overlying the lower bottom panel, a first divider formed from the divider panel and hingedly connected thereto along a line parallel to the connection between the divider panel and the second end panel, a glue area hingedly connected to the first divider along an edge parallel to the connection with the divider panel, a second divider hingedly connected to the glue area along an edge spaced from and parallel to the connection with the first divider, a glue tab hingedly connected to the second divider along an edge spaced from and parallel to the connection with the glue area, connecting portions formed from the upper bottom panel and each hingedly connected to the normally lower edge of a divider, said connecting portions being hingedly connected to the remainder of the upper bottom panel along lines which lie at an acute angle to the connections with the dividers.

5. A bottle carrier formed from a single blank of paperboard, comprising: a rectangular lower bottom panel, a rectangular side panel hingedly connected to the said bottom panel along a side edge thereof, a first rectangular end panel hingedly connected to an edge of the side panel adjacent the connection thereof with the bottom panel, a center panel of approximately the same size and shape as the side panel hingedly connected to the edge of the first end panel opposite the side thereof which is connected to the side panel, a second end panel of approximately the same size and shape as the first end panel hingedly connected to the edge of the side panel opposite the side thereof which is connected to the first end panel, a divider panel hingedly connected to the second end panel along the edge opposite the edge connected to the side panel, an upper bottom panel normally overlying the lower bottom panel, the divider panel and the center panel being fastened together in face-to-face relation with the divider panel facing the side panel, a first divider formed from the divider panel and hingedly connected thereto along a line parallel to the connection between the divider panel and the second end panel, a glue area formed from the divider panel and hingedly connected to the first divider along a line parallel to the connection thereof with the divider panel, a second divider hingedly connected to the glue area along a line parallel to the connection thereof with the first divider, a glue tab hingedly connected to the second divider along a line parallel to the connection thereof with the glue area, said glue tab being fastened in face-to-face relation to the said center panel, a triangular area formed from the upper bottom panel and connecting each of the dividers thereto, each triangular area being hingedly joined along one side to the bottom edge of its respective divider and being hingedly joined along another of its sides to the remainder of the said upper bottom panel.

6. A bottle carrier formed from a single blank of paperboard, comprising: a side panel, a center panel, a divider panel, a bottom panel, said center panel and said divider panel being fastened together in face-to-face relation and normally residing in spaced, parallel relation to the side panel with the divider panel facing the side panel, a divider extending from the divider panel to the side panel, an area hingedly attached to the first divider and fastened to the side panel in face-to-face relation therewith, the said divider extending downwardly between the panels to the bottom edges thereof, a connecting portion being hingedly attached to the bottom edge of the divider and being hingedly attached to the bottom panel along a line which lies at an acute angle to the line of attachment of the connecting portion to the bottom edge of the divider.
